UNITED STATES PATENT OFFICE

HERMAN M. GUMPER, OF JACKSON, MICHIGAN, ASSIGNOR TO THE MILES MANUFACTURING COMPANY, OF JACKSON, MICHIGAN, A COPARTNERSHIP

BUCKET CONVEYER

Application filed August 8, 1927. Serial No. 211,540.

This invention relates to an improvement in bucket conveyers.

The object of the invention is to provide for the carrying of a predetermined and measured quantity of material from a feed hopper by means of a conveyer of this character, provided with a plurality of buckets connected together in an endless arrangement and to allow of the feed hopper being located, if desired, beneath the surface of the floor or ground. The conveyer is designed for use in connection with concrete block machines, and to transport the mixed concrete from the feed hopper upward and discharge it into the mold of the block machine. However, the construction of the hopper and conveyer is such as to permit of its being used wherever desired for transporting plastic or other loose material, and it is not limited to its use with the concrete block machine.

The invention resides in the construction of the conveyer and the feed hopper together with a novel means of regulating the quantity of material carried in the buckets and leveling off the material in the top of the bucket, so that it only fills the bucket, not more than that, thus eliminating any spilling of the material as it is carried upward from the feed hopper.

A novel form of bucket is also used in connection with this conveyer which is also especially designed for plastic material and, as it passes through the feed hopper, it scoops the predetermined quantity of material from it, filling the bucket and, when the bucket has reached its discharge point, the material is all discharged by reason of the construction of the bucket.

In the accompanying drawings:

Fig. 1 is a side elevation of the invention;

Fig. 2 is a transverse sectional view through the head-shaft and associate mechanism;

Fig. 3 is a similar view through the drive-shaft;

Fig. 4 is a sectional view on the line 4—4 of Fig. 3;

Fig. 5 is a transverse sectional view on the line 5—5 of Fig. 1;

Fig. 6 is a similar view on the line 6—6 of Fig. 1;

Fig. 7 is a sectional view on the line 7—7 of Fig. 1;

Fig. 8 is a partial sectional view through the feed hopper and conveyer supports;

Fig. 9 is a sectional view on the line 9—9 of Fig. 8;

Fig. 10 is a perspective view of one of the buckets;

Fig. 11 is a longitudinal sectional view through the bucket; and

Fig. 12 is a transverse sectional view through the same.

The invention is designed for use in connection with concrete block machines but it is not limited to this use and may be used wherever desirable for transporting plastic or other similar materials. As shown in Fig. 1, the conveyer is in an inclined position and is supported upon a suitable framework designated generally by the numeral 1. This framework 1 supports the side channel-bars 2, which, in turn, support and brace the feeding conveyer. At their lower ends, the channel-bars 2 are connected to a side portion or lower hopper 3 of a feeding hopper 4, as shown in Figs. 1 and 8. The hopper bottom members 5 are in quarter section and are bolted together and to the lower portion of the portion 3 of the hopper 4, as shown in Fig. 1, to permit of these bottom sections being removed for cleaning and for cleaning out the hopper and removing all of the contents therefrom.

The hopper is supported upon a bracing member 6 at its lower end, as illustrated in Fig. 1. A tail-shaft 7 is rotatably mounted in bearings in the sections 3 and 5, and pulleys 8 are mounted on the tail-shaft 7 for free rotation within the bottom of the hopper 4, these pulleys being held in their proper relation with each other by means of a spacer 9, all of which is clearly shown in Fig. 7.

The head-shaft 10 is mounted in suitable bearings upon the channel-bars 2 and at the opposite ends of the latter from the tail-shaft 7. A sprocket wheel 11 is fixed on the head-shaft 10 and is driven by a sprocket chain 12 from a sprocket wheel 13 fixed on a drive-shaft 14, supported in suitable bearings 15 on the main frame 1. This drive-shaft 14

is driven by means of a pulley 16 from any suitable source of power, said pulley being mounted on the sleeve 17 extending outwardly from a clutch body 18, as shown in Fig. 3, 5 said clutch body being loosely mounted on the drive-shaft 14. An expanding clutch disk 19 is keyed to the drive-shaft 14 and is located within the clutch body 18, as shown in Figs. 3 and 4, and the clutch disk 19 is provided with arms 20 connected therewith for expanding the clutch disk and causing a clutching action between this disk and the internal surface of the clutch body 18. Set screws 21 extend through the arms 20 on opposite 10 sides of and in position to be engaged by a clutch cone 22, loosely mounted on the drive-shaft 14 and having a collar 23 thereon, carrying lugs 24, which are engaged by means of a yoke 25 pivoted as at 26 and having an outwardly extending arm 27, to which is connected a bell crank lever 28, which is connected with a rod 29, as shown in Fig. 1, leading to a clutch control lever (not shown) for operating the clutch. The yoke 25, which is 15 pivotally supported as at 26, is carried upon a bracket 30 mounted upon the main frame 1.

Sprocket wheels 31 are fixed upon the head-shaft 10, as shown in Fig. 2, in position to receive the sprocket chains 32, which also pass over the pulleys 8 on the tail-shaft 7. Buckets designated generally by the numeral 33 are secured to the links of the sprocket chains by means of rivets or other suitable fastening means 34.

The buckets 33 are shown more in detail in Figs. 10, 11 and 12, and it will be noted that the buckets are each formed of a base plate 35, side plates 36 and a back plate 37. The buckets are comparatively shallow and short, although their dimensions in this respect are not especially material. However, by referring to Fig. 11, it will be noted that the back plate 37 is approximately parallel with the front edges 38 of the side plates 36 and also that the angle between the back plate 37 and the base plate 35 is approximately 105°, whereas the angle between the front edges 38 and the base plate 35 is approximately 75°. This relationship between these parts enables the buckets to be placed close together upon the conveying chain, thus allowing them to discharge their contents in an approximately continuous stream or flow from the bucket conveyer. As shown in Fig. 12, the side plates 36 of each bucket 33 are inclined outwardly at an angle of approximately 105° from the base plate 35, thus making the side and back plates at substantially the same angle relative to the base plate of each bucket, and the front edges of the side plates at a complementary angle.

Skids 39 have the lower ends thereof secured to the portion 3 of the feed hopper, by means of bolts 40, and extend upwardly therefrom, as shown in Fig. 1, to support the chains 32

and the buckets carried thereby in their passage upward from the tail-shaft 7 to the head-shaft 10. On their return movement, the buckets are inverted, as shown in Fig. 6, and are supported by means of tightening rollers 41, mounted upon shafts 42 carried in brackets 43 mounted on the channel-bars 2. These tightening rollers 41 not only support the buckets 33 during their return passage but they also serve to keep the chains 32 tightened.

As shown in Fig. 8, a strike-off 44 is pivoted on pins 45 mounted in the hopper 4, and, as shown in Fig. 9, this strike-off is held against the top edges of the side plates 36 of the buckets 33 in order to rake off any superfluous material carried in the buckets before their passage from the hopper, so as to leave the buckets on the level full of the material and prevent any heaping up of the buckets which might allow the material to drop off during the upward passage of the buckets from the hopper and before the buckets reach their dumping positions. Arms 46 are connected with the strike-off 44 on opposite ends thereof and have pins 47 extending outwardly therefrom, to each of which one end of a spring 48 is connected, the opposite end of said spring being connected to a pin 49 at the sides of the lower hopper 3, as shown in Fig. 1. These springs exert a tension upon the strike-off 44 holding it in its proper position relative to the buckets, for regulating the quantity of material conveyed thereby.

A feed chute 50 is pivotally supported as at 51 upon the main frame 1, and extends into position to receive the material from the buckets as they pass over the sprocket wheels 31 on the head-shaft 10 to convey the material from the bucket conveyer to any suitable point desired.

A plate 52 extends across between and back of the channel-bars 2, as shown in Fig. 6, and substantially from the upper to the lower ends thereof, forming a return chute for any material that may stick to the buckets, returning it to the lower hopper 3, where it may again be picked up by the buckets.

In the operation of the conveyer, the rod 29 is shifted from the clutch control lever to rock the yoke 25 about its pivotal point 26 and to slide the cone 22 between the adjusting screws 21, which rocks the inner ends of the arms 20 outwardly, causing a tightening of the clutch disk 19 within the clutch body 18 and causing a driving action of the drive-shaft 14 from the pulley 16. Through the sprocket wheel 13 mounted on the drive-shaft 14 and the sprocket chain 12, motion is imparted to the sprocket wheel 11 and head-shaft 10, which drives the sprocket wheels 31 and the chain 32, thus setting the conveyer into operation. The buckets scoop up the material from the bottom hopper 3 during their upward passage and the material is

raked off level even with the tops of the buckets by the strike-off 44, and the buckets pass upward from the hopper, being supported during their upward movement upon the 5 skids 39.

While passing around the sprocket wheels 31, the buckets 33 dump the material conveyed thereby into the chute 50, which receives it and delivers it to any desired point. 10 During their return movement, the buckets are supported upon the tightening rollers 41, which also serve to tighten the chains 32 and any material which may remain in the buckets is returned to the lower hopper 3 by 15 means of the chute formed by the plate 52, carried by the channel-bars 2. The specific form of buckets allows them to be arranged closely together on the chains 32, and to carry a full load of material, either plastic or otherwise, and thus the material will be discharged 20 from the bucket conveyer in an approximately continuous flow or stream.

Thus, a new form of conveyer is devised, which is far superior to the usual form, in 25 which the buckets are closed on all sides except their top and dip up the material as they pass therethrough, the objection to these buckets being that they will not discharge all of the material conveyed thereby success- 30 fully, and they do not discharge the material in a substantially continuous stream or flow as is accomplished by the form of buckets used in connection with this invention. The feed is also regulated by means 35 of the strike-off associated with the buckets, thus preventing any spilling of the material as it is conveyed upward from the feed hopper.

I claim:

40 1. In a conveyer of the character described, the combination of supporting sprockets, an endless chain passing over the sprockets, a series of buckets mounted on the chain, skids extending longitudinally of the conveyer be- 45 tween the opposite ends thereof for receiving and supporting the chain during the outward movement of the buckets, rollers associated with the conveyer for engaging the edges of the buckets for supporting the buckets upon 50 the return movement thereof, and a chute associated with the conveyer upon the return side thereof.

2. In a conveyer of the character described, the combination of a drive-shaft, a sprocket 55 wheel mounted thereon, a tail-shaft, a pulley mounted on the tail-shaft, a sprocket chain supported by the sprocket wheel and pulley, a series of buckets carried by the sprocket chain in close proximity to each other, a 60 hopper associated with the conveyer, skids extending outwardly from the hopper longitudinally of the conveyer, for receiving and supporting the chain during the outward movement of the buckets, a supporting framework associated with the conveyer, and idle

rollers carried by said framework for receiving the edges of the buckets and supporting the bucket conveyer during the return movement thereof.

3. In a conveyer of the character described, 70 the combination of a drive-shaft, a sprocket wheel mounted thereon, a tail-shaft, a pulley mounted on the tail-shaft, a sprocket chain supported by the sprocket wheel and pulley, a series of buckets carried by the sprocket chain in close proximity to each other, a 75 hopper associated with the conveyer, skids extending outwardly from the hopper longitudinally of the conveyer, for receiving and supporting the chain during the outward movement of the buckets, a supporting framework associated with the conveyer, idle rollers carried by said framework for receiving the 80 edges of the buckets and supporting the bucket conveyer during the return movement thereof, and a plate extending across the framework forming a return chute.

4. In a conveyer of the character described, 85 the combination of a drive-shaft, a sprocket wheel mounted thereon, a tail-shaft, a pulley mounted on the tail-shaft, a sprocket chain supported by the sprocket wheel and pulley, a series of buckets carried by the sprocket chain in close proximity to each other, a 90 hopper associated with the conveyer, skids extending outwardly from the hopper longitudinally of the conveyer, for receiving and supporting the chain during the outward movement of the buckets, a supporting framework associated with the conveyer, idle 95 rollers carried by said framework for receiving the edges of the buckets and supporting the bucket conveyer during the return movement thereof, and a main drive shaft 100 operatively connected with and for driving the first-mentioned shaft.

5. The combination with a hopper, of an 105 endless bucket conveyer associated therewith and extending into the hopper, a strike off plate pivotally connected with the hopper and extending into position to engage the 110 bucket conveyer and rake off any superfluous material carried thereby level with the tops of the buckets, an arm connected with and extending outwardly from said strike off plate and resilient means connected with the arm for resiliently holding the strike off plate in proper relation against the bucket conveyer.

6. The combination with a hopper, of an 115 endless bucket conveyer associated therewith and extending into the hopper, the open top of the bucket conveyer being approximately parallel with the direction of travel of the conveyer, a strike-off plate extending at an angle thereto for raking off superfluous material, and means for pivotally supporting said strike-off plate adjacent the hopper.

7. The combination with a hopper, of an 120 endless bucket conveyer associated therewith

and extending into the hopper, the open top of the bucket conveyer being approximately parallel with the direction of travel of the conveyer, a strike-off plate extending at an angle thereto for raking off superfluous material, means for pivotally supporting said strike-off plate adjacent the hopper, an arm extending outwardly from the strike-off plate, and resilient means connected with said arm for resiliently holding the strike-off plate in proper relation against the bucket conveyer.

8. The combination of a main hopper, a lower hopper extending laterally therefrom and communicating with said main hopper, quarter sectional plates connected with and forming the bottom of the lower hopper, an endless conveyer extending into said lower hopper and the quarter sectional plates for receiving material therefrom and from the main hopper; and a bearing for the conveyer mounted at the juncture of the sectional plates.

9. An endless conveyer comprising a series of buckets, each of which has a flat bottom throughout and extends approximately parallel with the direction of travel of the buckets and having back and sides extending at obtuse angles to said bottom, said bucket having an open and unobstructed top and front, the sides of each bucket being in alignment with the sides of the next succeeding buckets, and terminating short of contact therewith.

33 In testimony whereof I affix my signature.
HERMAN M. GUMPER.
